(57) **CLAIM**

The ornamental design for a wall tray, as shown and described.

DESCRIPTION

FIG. 1 is a front perspective view of a wall tray showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of an alternative embodiment of the wall tray shown in FIG. 1;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

The broken line showing of the slits, holes, and screw portions is included for the purpose showing portions of the wall tray that form no part of the claimed design.
